DESIGN FOR A CIGARETTE AND CIGAR LIGHTER

EdWill Fisher, Minneapolis, Minn., assignor to Fisher Flame, Minneapolis, Minn., a copartnership

Application November 23, 1944, Serial No. 116,502

Term of patent 14 years

(Cl. D48—27)

To all whom it may concern:

Be it known that I, EdWill Fisher, a citizen of the United States and residing in the city of Minneapolis, Hennepin County, Minnesota, have invented a new, original, and ornamental Design for Cigarette and Cigar Lighter, of which the following is a specification, reference being made to the accompanying drawing, forming a part thereof, wherein:

Fig. 1 is a side and top perspective view of a cigarette and cigar lighter showing my new design with the cap closed;

Fig. 2 is a similar perspective view showing the cap open with the windshield and the part of the striker mechanism exposed;

Fig. 3 is a top plan view of the same with the cap swung into full open position; and

Fig. 4 is a front elevational view with the cap member in full open position.

I claim:

The ornamental design for cigarette and cigar lighter, substantially as shown.

EDWILL FISHER.
